U.S. Appl. No. 29/281,695, filed Jun. 28, 2007.

Primary Examiner — Sheryl Lane(74) *Attorney, Agent, or Firm* — Sterne, Kessler, Goldstein & Fox P.L.L.C.(57) **CLAIM**

The ornamental design for a display screen or portion thereof with graphical user interface, as shown and described.

DESCRIPTION

The FIGURE is a front view of a display screen or portion thereof with graphical user interface showing our new design. The broken lines around the FIGURE show a display screen or portion thereof and form no part of the claimed design. The broken lines within the FIGURE show unclaimed portions of the graphical user interface and form no part of the claimed design.
